United States Patent Office

Des. 230,321
Patented Feb. 5, 1974

230,321

PAPERWEIGHT OR SIMILAR ARTICLE

Milton Laser, 1 Overlook Ave., Great Neck, N.Y. 11021

Filed July 7, 1972, Ser. No. 269,844

Term of patent 14 years

Int. Cl. D19—02

U.S. Cl. D74—12

FIG. 1 is a front elevational view of a paperweight or similar article showing my new design;

FIG. 2 is a side elevational view thereof;

FIG. 3 is a side elevational view thereof, showing the side opposite that seen in FIG. 2;

FIG. 4 is a rear elevational view thereof; and

FIG. 5 is a top plan view thereof.

I claim:

The ornamental design for a paperweight or similar article, substantially as shown.
